UNITED STATES PATENT OFFICE.

MARIANUS X. TSCHUS, OF BLOOMINGTON, ILLINOIS.

SPRING-SNAP FOR BRIDLE-REINS.

Specification of Letters Patent No. 24,677, dated July 5, 1859.

To all whom it may concern:

Be it known that I, MARIANUS X. TSCHUS, of Bloomington, in the county of McLean and State of Illinois, have invented a new and useful Improvement in Spring-Snaps for Bridle-Reins and other Adjustable Portions of Leather Harness; and I do hereby declare that the following is a full, clear, and exact description of the construction 5 and operation of the same, reference being had to the annexed drawings, making a part of this specification, in which—

Figure 1 is an ordinary "spring snap," seen from the side, and Fig. 2 my improved "buckle-snap," seen from above and somewhat from one side, in perspective.

It is well known that "snaps" in ordinary use among harness-makers consist of a hook, of brass or other metal, with an adjusting spring under the point of the hook, which spring must be depressed before the hook can be unhitched, and a ring or loop, which terminates the shank of the hook, into which the bridle, or other strap to be hitched, 20 may be sewed. (See Fig. 1.) But I con-

struct my improved "snaps" so that the shank of the hook terminates in a buckle instead of merely a ring or loop, thereby dispensing with the necessity of sewing the bridle or other strap, to the "snap," the advantage of my combination of a snap and buckle in one being the facility with which such "snaps" may be adjusted to any required strap, without sewing.

I construct my buckle-snap by casting, or 35 otherwise forming it so that it will all be one piece of metal, except the "tongue" of the buckle, for the purpose of giving strength and beauty to the whole.

I do not claim to have invented either a 40 "snap" or a buckle; but

I claim—

The combination of the two in one, in the manner described and for the purpose described.

M. X. TSCHUS.
